UNITED STATES PATENT OFFICE.

JOHN W. HOLDSWORTH, OF ST. LOUIS, MISSOURI, ASSIGNOR OF ONE-HALF
TO ROBERT DODSWORTH, OF SAME PLACE.

INSULATING-CLAMP FOR ELECTRIC WIRES.

SPECIFICATION forming part of Letters Patent No. 350,365, dated October 5, 1886.

Application filed May 15, 1886. Serial No. 262,295. (Modcl.)

To all whom it may concern:

Be it known that I, JOHN W. HOLDSWORTH, of the city of St. Louis, in the State of Missouri, have invented a certain new and useful Improvement in Insulating-Clamps for Electric Wires, of which the following is a full, clear, and exact description, reference being had to the accompanying drawings, forming part of this specification, and in which—
10 Figures 1, 2, 6, 7, and 8 are perspective views showing the clamp in modified forms. Fig. 3 is a longitudinal section at 3 3, Fig. 4. Fig. 4 is a transverse section at 4 4, Fig. 3. Fig. 5 is a transverse section at 5 5, Fig. 3.
15 Fig. 9 is a detail longitudinal section in the central plane of the slot in which the wires are held.

This device, though cheap and simple in construction, is well adapted for the purpose intended, which is principally within doors, and for holding a number of parallel wires out of contact with each other and insulated from other objects. To enable this the blocks are made of wood or other insulating material, 25otted completely through parallel with its broad sides, except at a point near to one edge, the connection being so narrow that the other edge can be drawn in contact with the wires throughout its whole length. This drawing of the 30 lips together is done by the same nails or screws by which the clamp is attached to a wall or ceiling of a building.

The clamp is shown composed of a single block or strip, A, whose sides B are nearly 35 separated by a slot or kerf, C, shown parallel with the broad sides of the block.

D is a small post or connection at the edge b, which extends at its salient point d one-fourth (more or less) of the distance from the 40 edge b toward the edge b'. In the form of cleat shown in Figs. 8 and 9 this connection is placed centrally as to length of the cleat, as shown by the section-lines, in Fig. 9 and by broken lines in Fig. 8. In the form of 45 clamp shown in the other figures the connection D is at one corner of the clamp. The

nail or screw holes E are placed nearer to the edge b' of the clamp than the salient point d, so that when they are driven or screwed home the slot C at the edge b' shall be narrowed from 50 end to end of the cleat and the conducting-wires F held tight between the sides B along this line. The end or ends B' of the parts B are beveled, so as to make it easy to place the wires into the slot C by a side movement of 55 the wires. In Fig. 6 the inner faces of the sides B are shown with grooves B², by which the wires are held asunder before they are clamped fast by the approach of the sides B at the edge b'.
60

In Fig. 7 the clamp is shown with part of the slot C wider than the other part, to accommodate the clamp to wires of different gage.

In the use of the clamp it is attached by a nail or screw, G, in one of the holes E nearest to the connection D, said nail or screw not being forced home, so that the slot C is not closed in any degree. The wires may then be put in position, after which nails or screws are driven or screwed home in all the holes E, (or 70 as many as needed,) and the wires are thus fixed in position.

I am aware that an insulating-clamp for electric wires having two jaws separated by a kerf and connected together entirely across 75 one end is not new, and this, of course, I do not claim; but

I claim as my invention—

The insulating-clamp for wires, constructed, as herein described, of two jaws or members, 80 B B, nearly separated by a kerf, C, and connected only by a contracted post or bond, D, leaving three or more corners disconnected and free, so as to afford independent flexibility to the various parts of the clamp and 85 adapt it to hold or release the various wires separately, as explained.

JOHN W. HOLDSWORTH.
